ELECTRIC PLUG

William Huppert, New York, N. Y.; Ruth E. W.
Huppert executrix of said William Huppert, deceased

Application January 2, 1948, Serial No. 205

1 Claim. (Cl. 173—361)

1

This invention relates to an electric plug, particularly of the type known as a quick detachable plug for making electrical contact with an outlet, base, receptacle and the like.

The approved practice in detaching such a plug is to grasp the body instead of the wires. However, in many, if not in most, instances it is customary to detach the plug by pulling on the wires leading from the plug. Repeated detachment in this manner tends to break the wires, usually at the points where they are connected to the blades, or otherwise to weaken, and ultimately destroy, the electrical contact of the wires and the blades.

One of the objects of the present invention is to provide a plug construction that will overcome that objection, and will permit of repeatedly detaching the plug by pulling on the wires without resulting in loosening or breaking their contact with the blades.

Another object of the invention is to provide plug construction having a strain relief so that the harder the wires are pulled the tighter their insulation covering will be gripped.

A further object of the invention is to provide a plug construction that permits of quick and easy assembly of the blades and body.

A still further object of the invention is to provide a plug construction that is simple and economical to manufacture.

Other objects and advantages of the invention will appear from the following specification, reference being had to the accompanying drawings forming a part thereof, in which:

Fig. 1 is a side view of the plug;

Fig. 2 is a vertical longitudinal medial section of the plug, the wires being shown in full lines;

Fig. 3 is a vertical transverse section on the line 3—3 of Fig. 2 with the blade partly broken away;

Fig. 4 is a similar section with the blade and wires removed;

Fig. 5 is a vertical transverse section on the line 5—5 of Fig. 2;

Fig. 6 is a bottom plan view of the plug;

Fig. 7 is a fragmentary horizontal section on the line 7—7 of Fig. 2;

Fig. 8 is a perspective view of one of the blades before attachment to the plug;

Fig. 9 is a sectional view similar to Fig. 7 but with the blade and wires omitted; and,

Fig. 10 is a section on the line 10—10 of Fig. 2, also with the blade and wires omitted.

In general the plug comprises a hollow one-piece molded body 10 of insulating plastic ma-

2

terial or other suitable substance; a pair of blades 11—11 each having anchoring means at one end consisting of two prongs 12—12 that diverge in V-form and that have relatively sharp curved tips 13, which blades are anchored to the body in substantially the manner described in my co-pending application Serial No. 595,451 which matured into Patent No. 2,495,104 on January 17, 1950; and, two insulation covered wires 14—14 that are preferably joined together and the ends 15 of which are bared of insulation to make electrical contact with the blades.

The interior cavity of the hollow body 10 is substantially rectangular in shape, formed with integral vertical bosses 16 at its four corners and with other integral vertical bosses 17 spaced from the former. The spaces between the boss pairs 16—17 provide sockets in which the blades 11 are received. The length and breadth of the 15 sockets, measured horizontally, are a little larger than the corresponding width and thickness of a blade to provide a slight clearance between the blade and socket so that in assembling the parts 20 that in assembling the parts the blades may be freely inserted into the 25 sockets.

Walls or webs 18—18 are formed integral with and connect each pair of bosses 17 along their inner surface, said webs being thinner than the bosses, as seen in Figs. 7 and 9. Each web has a vertical slot 19 open at the bottom, as best seen 30 in Fig. 4, which slot is wider at its open bottom than at its upper portion. The opening into the slot is slightly greater in width than the diameter of an insulated wire 14 so that the wire 35 may be easily inserted into the slot. However, since the width of the upper portion of the slot is less than the diameter of the wire, the insulation covering of the wire will be constricted by the slot as the wire is pulled up into it, and the edges 20 of the narrow portion of the slot will 40 tightly grip the insulation, thus providing a strain relief for the wire. To assist in gripping the insulation the edges of the slot are preferably bevelled. A hole 21 extends vertically through the central axis of the body 10 for passage of the wires into the interior cavity of the plug.

On reference to Fig. 7 it will be seen that the spacing between the opposed faces of blade 11 and wall 18 is slightly less than the normal thickness of a covered wire 14. Accordingly, the insulation covered portion of the wire that is confined in that space will be distorted from its normal shape, that is to say, it will be compressed in one direction and elongated in the direction 55 at a right angle to the first. The distortion of

the insulation wedges the wire tightly in this space and affords an additional strain relief.

It will be apparent that the strain reliefs afforded by this construction will effectually prevent breaking of electrical contact between the blades and the wires on detaching the plug by pulling on the wires instead of gripping the body.

The bared ends 15 of the wires are bent about the anchored ends of the blades 11 and are tightly gripped between said ends and the opposed portions 22 of the body cavity, as seen in Fig. 2.

In assembly, the blades are inserted in contact with the wires into the blade-receiving sockets. The prongs 12, which normally form a V with each other, as shown in Fig. 8, are then spread to assume the substantially horizontal position shown in Fig. 5. As hereinbefore noted, the spreading is effected only after free insertion of the blades into their sockets. In the spreading movement, the relatively slender curved tips 13 of the prongs will bite into the material of the body and on meeting the resistance thereof will bend or curl in the direction of their curvature without exerting any undue pressure on the material and will thus form recesses 23 in which the spread prongs of the blades are held or anchored. The provision of prongs that operate in this manner constitutes an improvement of the anchoring devices of my copending application, hereinbefore referred to, in that the easily bendable curved tips of the prongs limit the pressure that the prongs exert on the material on being spread, and thereby practically eliminate any danger of breakage of the body in securing the blades thereto.

Various modifications in the details of the construction herein described and illustrated in the accompanying drawings may be made within the spirit and scope of the invention.

I claim:

An electric plug comprising a hollow body hav-

ing an aperture at one end for entry of a pair of insulation covered lead wires and open at its other end, said body having blade receiving sockets at opposite sides thereof, and internal partitions each having a constricted passage with parallel edges opening into one of said sockets through which the lead wires pass, the effective width of said passages being less than the diameter of the insulation covered wires to grip the insulation tightly between the edges of said passage to afford a strain relief, the ends of the wires passing into said sockets beyond said passages being bared of their insulation covering, and a blade having an end portion in each socket, each blade having a pair of prongs diverging outwardly from said one end to an extent greater than the width of the blade with the tips of said prongs engaged in the side walls of the socket, the bared end of each wire being bent about said lower end of the blade to make electrical contact therewith, the portion of said bared end that passes under the prongs being tightly wedged between said prongs and the closed end of the socket in which the blade is secured.

WILLIAM HUPPERT.
